UNITED STATES PATENT OFFICE.

WILLIAM H. STRONG, OF SARDINIA, NEW YORK, ASSIGNOR, BY MESNE ASSIGNMENTS, TO U. S. STANDARD VOTING MACHINE CO., OF ROCHESTER, NEW YORK, A CORPORATION OF NEW YORK.

VOTING-MACHINE.

No. 889,985.

Specification of Letters Patent.

Patented June 9, 1908.

Application filed January 29, 1898. Serial No. 668,442.

To all whom it may concern:

Be it known that I, WILLIAM H. STRONG, a citizen of the United States, residing at Sardinia, in the county of Erie and State of New York, have invented a new and useful Voting-Machine, of which the following is a specification.

My present invention relates to voting machines and particularly to the interlocking mechanism thereof, and has for its object to provide mechanism of such construction and arrangement that while the voter may indicate a proper choice of candidates or measures in secrecy he cannot indicate or vote for more than a predetermined number. Said mechanism and the parts thereof are also constructed and arranged so that the indicators or operating parts may be formed into groups including a greater or lesser number of indicators, to adapt the machine for multi-candidate and single candidate voting, without impairing, varying or affecting their separate operation, and also without interfering with their arrangement in party and office lines or columns.

The invention further has for its object to provide a movable part or member so related to the intercommunicating parts of the mechanism as to maintain proper co-operative relation therewith under all conditions of adjustment, this contributing to the results above mentioned and being capable of use in other connections.

Further objects and advantages of this invention will appear in the following description, and the novel features thereof will be particularly pointed out in the appended claims.

In the drawings—Figure 1 is a perspective view showing the exterior of a booth embodying a voting machine constructed in accordance with my invention. Fig. 2 is a rear view of the casing of the voting mechanism, the rear wall and false back being partly broken away to show the interior mechanism. Fig. 3 is a front view of the voting-mechanism casing, as seen from the interior of the booth. Fig. 4 is a horizontal section of the voting mechanism. Fig. 5 is a vertical sectional view of the same in the plane of one of the vertical series of movable parts or voting-keys. Fig. 6 is a detail plan view of the tally mechanisms and co-operating parts used in connection with "amendment" and "question" voting. Fig. 7 is a

plan view of a series of disks constituting a tally mechanism. Fig. 8 is an edge view of the same. Fig. 9 is a detail view in perspective of one of the tilting-stops and contiguous locking-bolts. Fig. 10 is a detail plan view of a slightly modified construction of voting-key lock and resetting device. Fig. 11 is a detail view, with the contiguous portion of the casing in vertical section, of the means for communicating motion from the booth-door trip to the resetting-frame. Fig. 12 is a plan view of the booth as seen when folded.

Similar numerals of reference indicate corresponding parts in all the figures of the drawings.

The particular machine shown embodies a suitable casing 1, having a rear door or doors 2, and within which are arranged horizontal series of movable parts consisting of voting-keys 3, arranged to slide horizontally, and having reduced neck-portions projecting beyond the face of the casing and terminating in buttons 4, or their equivalents. The rear ends of the voting-key blades operate in suitable guide-openings 5 in a partition 6, preferably spaced from the rear wall of the casing to form a compartment, for a purpose hereinafter explained, and arranged in front of this partition are tally mechanisms, one for each movable part or voting-key, each tally mechanism consisting of disks 7, 8, 9, of any desired number, and referred to hereinafter, respectively, as units, tens, hundreds disks, etc. These disks are provided with peripheral series of numerals for exposure through inspection-openings 10 in said partition 6, whereby, when the doors in the rear wall of the casing are closed, the result of the voting is concealed, whereas by opening said doors, the result of the votes cast for different candidates may be read through the inspection-openings. Obviously, this reading of the number of votes cast is made after the closing of the polls.

In the construction illustrated, the units tally-disk is mounted upon a vertical pivot, and is provided, on its upper face, with a plurality of beveled projections 11 forming ratchet-teeth for alternate engagement by spaced operating-teeth 12 and 13 on the contiguous voting-slide, which preferably passes over the units-disk contiguous to the plane of the ratchet-teeth, said operating-teeth depending from the slide, and hence, operating

in the plane of the ratchet-teeth. In practice I prefer to separate the bases of the ratchet-teeth a sufficient distance to allow the operating-teeth of the slide to pass there-between, as shown in the drawings. Assuming that each units-disk has ten ratchet-teeth (the tally mechanism being preferably constructed in accordance with the decimal system), the movement of the co-operating voting-slide in one direction will cause the tooth 12 to engage the beveled face of the ratchet-tooth which is in the path thereof, and advance said units-disk a distance equal to one-twentieth of a revolution. This movement of the slide carries the rear tooth 13 out of the path of the ratchet-teeth to allow the apex of the contiguous ratchet-tooth to pass the inner end of said operating-tooth 13. Hence, upon the return movement of the voting-slide, the front end of the rear tooth 13 will engage the beveled surface of another ratchet-tooth, and will advance the disk through another twentieth of a revolution, thus completing a tenth revolution, necessary to indicate that a vote has been cast by the operation of the co-operating voting-slide. In other words, each units-disk is capable of a step-by-step movement, each step consisting of an angular movement of one-half that necessary for indicating a vote, whereby when a voting-key has been operated by the occupant of the booth, he communicates to each tally mechanism only one-half of the movement which is necessary to indicate a vote, and the return of the voting-keys must be accomplished in order to complete the indication. This regular step-by-step movement of each units-disk to effect the proper operation of the succeeding disks is secured by reason of having the operating teeth disposed parallel with the longitudinal plane of the key and arranged at the same side of the axis of the units-disk. This is plainly shown in Fig. 4 of the drawings, and is also true of the modification illustrated in Fig. 10 of the drawings.

The tens-disk 8 of the tally mechanism is provided with a series of radial stop-teeth 14, and the periphery of the tens-disk is arranged in such a position with relation to the periphery of the units-disk, that the two contiguous stop-teeth which are adjacent to the periphery of the units-disk are adapted to bear terminally against the surface of said units-disk, and thus lock the tens-disk against independent rotation, while the units-disk is free to rotate. In the same way, the hundreds-disk 9 is provided with peripheral radially-projecting stop-teeth 15 to bear terminally against the contiguous rounded surface of the tens-disk, as shown clearly in Fig. 7, and thus lock the hundreds-disk against rotary motion, while the tens-disk is free to rotate independently thereof. Furthermore, the units-disk is provided with a trip-lug or arm 16

adapted to engage either of a series of operating-teeth 17 which project upwardly or parallel with the axis of the tens-disk, and in the periphery of the units-disk, slightly in rear of the trip-arm 16, is arranged a socket or depression 18. Hence, when the units-disk has made one complete revolution, lacking one double step, or has completed nine double steps (a "double step" consisting of that movement of a tally-disk which is necessary to indicate that a vote has been cast), the socket or depression 18 will come into alignment with one of the stop-teeth 14 of the tens-disk, and simultaneously the trip-arm 16 will come into contact with one of the operating-teeth 17 of the tens-disk. Therefore, a further movement of the units-disk will cause the trip-arm to advance the tens-disk, while the stop-tooth of the tens-disk passes into the socket or depression 18. When the units and tens disks have made a double step in unison, in order to carry the tens of the count to the tens-disk, the succeeding stop-tooth of the tens-disk will come in contact with the continuous or unbroken surface of a units-disk, and said tens-disk will be again locked against forward movement, until the units-disk has completed a second revolution. The communication of motion from the tens-disk to the hundreds-disk is accomplished by analogous mechanism, said tens-disk being provided with a radial trip-arm 19 for engagement with either of a series of operating-teeth 20 projecting axially from the hundreds-disk. Thus, it will be seen that the communication of motion from each disk of a tally mechanism to the next of higher denomination is accomplished by the positive engagement of a trip-arm on the disk of lower denomination with an operating tooth on the contiguous disk of next higher denomination, while, in the interval between such engagement of the trip-arm with an operating-tooth, the disk of higher denomination is positively locked against rotary movement by the engagement of two contiguous stop-teeth thereon with the continuous peripheral surface of the disk of lower denomination. In the drawings, I have illustrated tally mechanisms, each of which embodies only three co-operating disks, but it will be understood that any desired number thereof may be employed to suit the conditions under and localities in which a machine is to be used.

In order to prevent "repeating" or successive operations of the same voting-key, I provide each key with a locking device consisting, in the construction illustrated, of a pawl 21, having a shoulder 22 for engagement with a fixed stop 23, said shoulder being preferably undercut or beveled, to prevent the accidental disengagement of the pawl from the stop. I desire, however, to avoid the use of springs, or other yielding

means, for throwing the pawls into engagement with the stops (as being liable to become disarranged or put out of order), and, therefore, each pawl is provided with a trip-
5 cam 24, for contact with the front edge of the stop 23, or other equivalent fixed object in its path, to positively throw the pawl into the engaged position required. The opposite or releasing movement of each pawl is limited
10 by a stop 25 carried by the voting-key.

Various means may be employed for disengaging the locking-pawls from the stops and returning the voting-keys to their longitudinal or normal positions after the completion
15 of the operations of each voter. That form of resetting mechanism which I have illustrated in Figs. 4 to 6, inclusive, and 11, consists of vertical bars 26 forming parts of a resetting-frame which is mounted for forward
20 and rearward movement in the casing, and preferably in that compartment thereof which is in rear of the exposed partition 6, said upright bars being connected by suitable cross-bars 27, and projecting forwardly
25 through suitable slots in the partition 6, for contact with the vertical series of locking-pawls. These pawls are provided with bevel or cam-faces 28, which, when the pawls are in engagement with the stops 23, are
30 located in the paths of the forward movement of the bars 26, whereby, when the resetting-frame is moved forwardly, the front edges of the bars 26 will first engage the bevel or cam-faces 28, to draw the locking-pawls
35 out of engagement with the stops 23, and will then bear against the pawls to push the voting-keys forwardly to the positions indicated clearly in Fig. 4. The means which I have illustrated in the drawings for
40 operating this resetting-frame include guides 29 having pins 30 engaging slots 31 in the bars 26, yielding returning devices, such as weight-cords 31^a, (see Figs. 4 and 5) and an advancing or operating-cord or connection
45 32, adapted to be actuated by trip mechanism, fully explained hereinafter. The straining of the operating-cord 32 draws the resetting-frame forward to return the movable parts of the voting mechanism to their operative positions, and the release of said operating-cord allows the counterbalancing devices
50 to return said frame to its normal position, as indicated in Fig. 4.

In the modified construction illustrated in Fig. 10, the locking-pawls 21^a are adapted to coöperate with a fixed stop 23^a, as hereinbefore described in connection with the preferred construction, but the resetting-frame consists of bars or rods 26^a arranged respectively parallel with the horizontal series of voting-keys and adapted, when moved forward, as indicated by the arrows in Fig. 10, to engage trip-arms 28^a on the pawls, and thus (by swinging the trip-arms forward until

checked by a stop 28^b) disengage the pawls 65 from the stops 23^a and return the voting-keys.

Parallel with each horizontal series of voting-keys is a series of key-locking bolts 33, one bolt being arranged between each two contiguous voting-keys of a horizontal series; 70 and interposed between the contiguous extremities of adjacent locking-bolts is a spreader 34 of wedge or analogous shape, for insertion between said contiguous extremities of the locking-bolts to separate the same.

In general-ticket voting the locking-bolts in each horizontal series are of such lengths that there is space in each series for the advance of only one spreader, whereby when the voting-keys assigned to the candidates placed in the field by each political party are arranged in vertical series, as indicated in Figs. 2 and 3, the corresponding candidates of the different parties being arranged in the same horizontal series, said relative arrangement of the locking-bolts and spreaders prevents a voter from casting more than one vote for a candidate for any particular office. For instance, if he votes for the candidate of the republican party for governor, all of the voting-keys in the same horizontal series, and representing the several candidates, for governor, of the other political parties, are locked. These spreaders are carried and actuated, respectively by the voting-keys, and the contiguous extremities of the locking-bolts are held in their normal aligned positions, against vertical displacement, by the contact of the voting-keys with the upper surfaces of the locking-bolts, as will be seen by reference to Fig.

5. In the construction illustrated, the spreaders are provided with upwardly-extending lugs or slides 35, which engage guides or slots 36, formed transversely in the voting-keys, said keys being provided with suitable lateral guide extensions 37 for this purpose. Therefore, when the voting-key is pushed to indicate a vote, the spreader which is connected therewith is carried between the contiguous extremities of the adjacent locking-bolts, and the locking-bolts in that horizontal series are adjusted to exclude the spreader belonging to any other voting-key, as hereinbefore explained, and the slotted connection between each spreader and its voting-key, allows that lateral movement of the spreader with relation to its voting-key, which will permit the required adjustment of the locking-bolts without imparting lateral pressure to the voting-keys.

Arranged at the ends of the horizontal or longitudinal series of locking-bolts are stops 38, against which the outer extremities of the terminal locking-bolts abut, but for the purpose of class-voting these stops are pivotally mounted for tilting movement, the same being adapted to be locked in fixed positions, during general-ticket-voting, by means of

locking-pins 39, of which the heads are accessible from the compartment in rear of the inspection-partition 6, as shown in Fig. 4. These locking-pins are fitted in suitable 5 guides 40 in the casing, and are adapted to engage openings or sockets 41 in the tilting-stops, see Fig. 9.

In group-voting, as for presidential electors, constables, etc., it is necessary to provide 10 means whereby a voter may cast ballots for a given number of candidates, irrespective of party, and hence it is necessary to provide means whereby voting-keys in the same horizontal series may be operated. If, for example, a voter is entitled to cast votes for 15 five electors, or other officers, a sufficient number of the tilting-stops should be released, by disengaging the locking-pins 39 therefrom, to connect five horizontal or longitudinal 20 series of locking-bolts to form a single group. For instance, referring to Fig. 2, it will be necessary, in order to connect five horizontal series of locking-bolts in a group, to release the tilting-stops *a* and *b* at one end 25 of the series, and *c* and *d* at the opposite end of the series, leaving *e* and *f* locked. Now, as there is only space in each horizontal series of locking-bolts to receive one spreader (when the stops are fixed), it is obvious that 30 by releasing the stops *a*, *b*, *c* and *d*, there is sufficient space in the five connected series of locking-bolts to receive five spreaders, and in operation the votes may be distributed, as desired; that is, any five voting-keys comprised 35 in the five connected series, may be operated. But when the fifth voting-key has been actuated, all of the space allowed for the voter will have been filled, and hence, all of the remaining voting-keys in the said 40 connected series will be locked against repression. For instance, with the stops *a*, *b*, *c* and *d* released, it is obvious that if there is space in each series of locking-bolts for the introduction of a single spreader, there will 45 be a combined space in the five series, at the ends of which said stops *a*, *b*, *c* and *d* are located, for the reception of five spreaders. Therefore, if a voting-key in the uppermost 50 of the combined series is actuated, the space of one spreader in the series of locking-bolts at the upper end of the stop *a* will be taken up, without affecting the stop *a*. If a second voting-key in the same series is actuated, the locking-bolts will be advanced toward the 55 left, (see Fig. 2) to tilt the stop *a* sufficiently to allow the spreader of said voting-key to enter both the extremities of the adjacent locking-bolts. The stop *e* cannot move because it is locked by the means provided for 60 that purpose. Said tilting movement of the stop *a* has pushed the locking-bolts in the series at the lower end of the stop *a*, and the upper end of the stop *e* together, so that now there is no space in said second series. If a 65 third voting-key of the upper or first series is

operated, the bolts will again be pushed toward the left, to still further tilt the stop *a*, but as all of the space in the second series of locking-bolts, or that at the lower end of the stop *a* has been taken up by the previous 70 movement of the second voting-key, the said motion of the stop *a* will tilt the stop *c*, and thereby take up a single space in the series of locking-bolts at the lower end of the stop *c*. The operation of the fourth key in the 75 upper or first series will still further advance the locking-bolts of said series toward the left, thereby still further tilting the stop *a*, also still further tilting the stop *c*, and communicating motion through the series of locking-bolts of the lower end of the stop *c* to the stop *b*. This movement, obviously, takes up the vacant space in the series of locking-bolts at the lower end of the stop *b*, or, in other words, between the stop *b* and the 80 stop *d*. Again, upon the operation of the fifth voting-key in the first or upper series, the locking-bolts in said series will again be advanced to the left, thus still further tilting the stops *a*, *c*, and *b*. This movement of the 85 stop *b* will be communicated through the series of bolts at the lower end thereof to the stop *d*, and the latter will be swung out of its normal position to take up the space in the fifth series of locking-bolts, or that at the 90 upper end of the stop *f*. Thus, all of the spaces in the fifth series of locking-bolts have been taken up by the operation of five voting-keys in the uppermost of the connected 95 series, or that which is at the upper end of 100 the stop *a*, and no other voting-key, either in said uppermost series, or in any other of the connected series, can be operated, because the stop *e* is locked at one end of the connected series, and the stop *f* is locked at the 105 other end of the connected series. This operation will be followed in actuating a plurality of voting-keys in either of the series which are connected for cumulative voting, and it is obvious that any desired number of 110 series may be connected, one additional space being added for each series, whereby a number of voting-keys equal to the number of connected series may be voted, either all in one series, or distributed, as may be preferred 115 by the voter, and when voting-keys equal in number to the connected series have been actuated, this portion of the apparatus is locked to prevent the movement of any other voting-keys in the connected series. In the 120 same way, any desired number of horizontal series of voting-devices may be connected to form a group, to suit the number of votes to which each occupant of the booth is entitled, or, in other words, to suit the number of representatives or candidates to be elected from that district, ward, or other electoral section.

On the rear or exposed face of the casing which incloses the voting 'mechanism' is placed a guide or instruction sheet, shown in 130

Fig. 2, representing the plan of the push-buttons and the offices for which candidates are nominated by the several parties, whereby a voter, before entering the booth, may be instructed by a suitable inspector or other officer of the election, as to how to operate the push-buttons in order to produce the result which said voter may desire. After receiving such instructions, the voter is in possession of sufficient information to enable him to vote intelligently and without asking specific questions after entering the booth, or after having commenced the voting operation. The face or front surface of the casing, which is exposed within the booth, corresponds exactly, in the plan of its push-buttons, names, etc., with the instruction plat upon the exposed rear side of the casing, the keys being numbered consecutively from top to bottom to serve as a guide for the voter. At the right of the machine below the questions and amendments column is an irregular-ballot receptacle 42 having a ballot-receiving slot 43, and arranged contiguous to said box is a vertical column or series of irregular-voting keys 44. For each irregular vote which an occupant of the booth desires to deposit in the receptacle 42, he must operate a push-button in the irregular-voting column corresponding with the office for which said irregular vote is to be cast, thereby locking out the remaining voting-keys in the same horizontal series. Upon pressing a key in the irregular-voting column, a ballot, suitable for casting a vote for that officer, such as governor, lieutenant governor, mayor, etc., will be furnished to the voter by the inspectors or judges of the election, whereupon, without leaving the booth, the desired non-nominated name, selected by the voter, may be written upon the ballot, and the latter deposited in the receptacle.

Any suitable means, forming no part of the subject-matter of my invention, may be employed for indicating when an irregular-ticket voting-key has been operated to lock the regular-ticket voting-keys in the same series, and designated respectively by the nominated candidates. I have deemed it unnecessary to illustrate any specific means for thus apprising the judges or officers of the election of the preferred ballot desired by a voter, as various means, well known in the art, may be employed in this connection.

The construction and operation of the questions and amendments voting devices are identical with those of the voting mechanisms hereinbefore described, with the exception that the relative positions of the tally mechanisms for the "yes" and "no" keys or slides are reversed, to dispose said keys or slides at a greater interval, as will be seen by reference to Figs. 2, 3 and 6. Also, as shown in Fig. 2, locking-bolts 33^a are used in connection with the questions and amendments

voting-keys, with the movable, or pivotal stops 38^a arranged in the paths of the outermost members of the bolts, as hereinbefore described. The tilting stops 38^a used in connection with the locking-bolts of the 70 amendment voting devices are not absolutely necessary in voting for amendments or other constitutional questions, but I preferably construct the machine with said stops included, as it enables me to use this portion 75 of the mechanism for other purposes when constitutional or amendment questions are not taken into consideration.

In order to insure the strict secrecy desired and required in the casting of the votes, 80 I have constructed a machine wherein the operation of each voting-key or movable member is independent of that of every other key or movable member, whereby each vote must be cast separately, and in the path of 85 each voting-key button, as will be seen by reference to Figs. 4 and 5, I arrange cushions 45, of rubber, or its equivalent, to receive the impact of said button, when a key is repressed, and thus absorb the jar. Furthermore, the use of springs is avoided, in order 90 to dispense with any snap or rebound in the movement of the parts. When a voting-key is repressed, the trip 24 of its locking-pawl comes in contact with the fixed stop arranged in the path thereof, and the pawl is thereby thrown laterally into position for engagement with the stop 23, said operation being accomplished noiselessly. The reason 95 for this noiseless engagement of the pawl with the stop 23 is that the swinging movement of the pawl is in a horizontal plane, and no springs or other means adapted to form a snap at the moment of engagement are utilized. As the pawl advances to bring its 100 cam-face 24 into contact with the front edge of the stop 23, the pawl is swung quietly to its engaging position. The trip 24 is arranged at one side of a line parallel with the direction of movement of the pawl taken 110 through the pivot thereof, or, in other words, is arranged eccentrically with relation to the pivot of the pawl, and hence when said trip comes in contact with a fixed object, it is 115 obvious that the portion of the pawl in advance thereof receives a lateral movement, which causes its engagement with the rear end of the stop 23. Thus, all of the voting operations of the machine may be accomplished without producing any distinctive 120 sound which may be detected from the outside of the booth, or interpreted to indicate to persons in the vicinity, what votes are being cast by the occupant of the booth.

It is necessary, in addition to the above 125 described mechanism, to provide such means for supporting the casing, that it may be raised or lowered to suit the height or reach of the occupant of the booth. For instance, a cripple or invalid wheeled into the booth in 130

a chair would require the keyboard to be lowered to bring it within reach, because his votes must be cast by himself, and not through the assistance of a second person. 5 Hence, I provide the casing with vertical telescoping front and rear supports 46 and 47, the former of which comprise tubular members 48, fixed to the casing in any suitable manner, and core or inner members 49 fitted to slide in said tubular members, and having racks engaged by pinions 50 which are carried by a spindle 51 with which, by means of intermeshing bevel gears 52, is connected an operating-crank 53. By turning 10 the crank the casing may be raised or lowered, as desired. The rear standards or supports 47 consist of telescoping outer and inner members 54 and 55, and at the outer corners of the booth 56 are arranged standards or supports 47^a corresponding with those above described. In order to facilitate the folding of the booth and its attachments, I preferably secure the tubular members of the supports or standards to the frame or 20 casing by means of staples or keepers 57 having suitable locking devices, such as set-screws 58, for locking said tubular members at the desired extension, or folded within the casing, as indicated by dotted lines in Fig. 5. 25 The fixed or inner members of the supports may, as shown, be provided at their lower extremities with floor plates 59 for attachment by means of screws, or other securing devices, to the floor, in order to steady the structure when open. The construction of 30 booth which I prefer embodies side walls 60 and 61, respectively hinged to the frame of the casing 1, and an end wall 62 which is hinged at one edge to the wall 60, said walls 40 61 and 60 being preferably provided, respectively, with inwardly-opening entrance and exit doors 63 and 64; and in the path of the latter is arranged a trip-lever 65, of bell-crank or analogous construction, connected 45 with the resetting cord 32. When the exit door 64 is opened to allow the occupant of the booth to pass out, it engages the contiguous arm of the trip-lever and draws upon the cord 32 to advance the resetting-frame, 50 and thus return the voting devices to their normal or operative positions.

It will be seen that when the booth is not in use the standards or supports may be folded, by disengaging the core or inner members thereof from the tubular members, and sliding the latter upwardly into the casing, or wholly removing the same, whereupon the booth walls may be folded, as indicated in Fig. 12, to occupy positions parallel with 60 and covering the face of the voting-mechanism casing.

Also arranged in connection with the booth is a speaking-tube 66 of any ordinary construction, see Fig. 1, through which communication may be had by a judge or inspector

of the election with the occupant of the booth, to give instructions or answer inquiries, in connection with the casting of irregular votes, etc.

Various changes in the form, proportion, 70 and the minor details of construction may be resorted to without departing from the spirit or sacrificing any of the advantages of this invention.

The keys and their locking devices and the 75 arrangement of the locking devices constitute the subject matter of a divisional application and are not herein claimed.

Having described my invention, what I claim is—

1. In a voting machine, the combination with the tally mechanisms, and the voting keys for operating the same, of a plurality of terminally disconnected, independently movable locking bolts, and a spreader for each 85 voting key and having a slideable interlocking engagement therewith, and interposed between the contiguous extremities of two adjacent locking bolts, each spreader being movable with its voting key transversely of 90 and between the adjacent bolt ends, and also movable with the bolts independently and transversely of the key without affecting its slideable interlocking engagement therewith, substantially as set forth. 95

2. In a voting machine, the combination with the tally mechanisms and individual keys for operating the same, of a plurality of horizontal series of disconnected aligned locking bolts, spreading elements having slideable 100 interlocking connection with the keys so as to be movable therewith and also independently thereof, said spreading elements being adapted to work between the contiguous extremities of adjacent locking bolts, devices 105 for connecting the bolts of any number of series for movement in unison to permit a plurality of keys within the area of the connected series to be operated, and locking means for securing said devices in fixed position to convert them into stops for the bolts associated therewith, substantially as set forth. 110

3. In a voting machine, the combination with movable parts and tally mechanisms, 115 of locking-bolts arranged in series in operative relation with said movable parts, spreaders carried and actuated by said movable parts, for longitudinally adjusting the bolts, tilting stops in the paths of the terminal locking-bolts of the series to communicate motion from those of one series to those of another, and a separate locking pin associated with each stop, to secure it in a fixed position, substantially as specified. 120

4. In a voting machine, the combination, 125 of voting-keys and tally mechanisms, locking-bolts arranged in series transversely to the motion of the voting-keys, said keys being provided with slots arranged parallel 130

with the locking-bolts, spreaders interposed between the contiguous extremities of adjacent locking-bolts and having lugs fitted in the slots of the voting-keys, and movable 5 means for communicating motion from the terminal bolt of one series to the terminal bolt of the contiguous series, substantially as specified.

5. The combination in a voting machine, 10 of a plurality of rows or series of ballot indicators, a corresponding plurality of rows of registering mechanisms therefor, a plurality of interlocking mechanisms one for each row of indicators arranged parallel therewith and 15 adapted to permit the simultaneous or successive operation to voted position of only a predetermined number of indicators in a row, each indicator operating separately upon and remaining in engagement with its interlocking mechanism when moved to voting 20 position and each row of indicators and its interlocking mechanism constituting a group, means for limiting the movement of the interlocking mechanism in each row and 25 means for connecting a plurality of said rows of interlocking mechanisms in a continuous series to form a multicandidate group.

6. In interlocking mechanisms for party 30 column voting machines, the combination of push rods, transverse guides reciprocating therewith, spreaders freely movable on said guides and reciprocating therewith, and devices between the spreaders and moved 35 thereby, substantially as described.

7. In a voting machine, the combination 40 of voting mechanism, limiting mechanism therefor and a pin and slot connection between said mechanisms movable in the direction of movement of the voting mechanism.

8. In a voting machine, the combination 45 of a voting key, a limiting mechanism and a pin and slot connection between said key and said mechanism, said pin and slot being movable in the direction of movement of the key.

9. In a voting machine the combination 50 with the frame, of the counting mechanism, separators, a series of blocks operable by said separators and preventing the operation of more than a certain number thereof, a transmitting member operated upon by one of said blocks, said member being movable with said wedge blocks, and means for securing said member.

55 10. In a voting machine, the combination of two or more superposed tiers or rows of voting mechanisms one for each office, with a system of limiting wedge blocks for each tier and operated by or with the voting 60 mechanisms thereof, and movable stop devices capable of being set to operatively connect for movement the systems of wedges of any two or more superposed tiers.

11. In a voting machine the combination 65 of a number of tiers of voting mechanisms

for different kinds of offices and each tier having its own limiting mechanisms parallel therewith and the limiting mechanisms of all said tiers being connected together one after the other in succession for interoperation and 70 the connection thereof permitting one voter to operate as many voting mechanisms as there are tiers, selecting the same from any of said tiers, the extreme ends of the limiting mechanisms as a whole being independently 75 secured.

12. In a voting machine the combination 80 of a number of tiers of voting mechanisms for different offices each tier having its own limiting mechanism, the limiting mechanisms of all said tiers being interconnected for interoperation, and means whereby desired limiting mechanisms may be locked against communication of the movement to adjacent mechanisms.

85 13. A voting machine comprising a number of tiers of counter devices and associated mechanisms, including a limiting mechanism in each tier, said limiting mechanisms comprising rigid parts only and movable by the voter, positive couplings between all the tiers of limiting mechanisms and movable therewith permitting one step movement of each independent of the others.

90 14. In a voting machine the combination 95 of two or more tiers of voting mechanisms with a limiting mechanism for each tier, said limiting mechanisms being parallel, one step connections between said limiting mechanism and movable therewith with relation to the frame of the machine whereby each limiting mechanism as a whole is permitted a single movement independent of the others, while further movement of such limiting mechanism will be communicated 100 to the other or others.

105 15. In a voting machine, the combination 110 of two or more tiers or rows of voting mechanisms, each for one office, with rigid limiting mechanism parallel with each tier, one step connections between said limiting mechanisms adapting the same for inter-operation or co-operation in a multi-candidate group but permitting the operation of one voting mechanism in each tier without affecting the limiting mechanisms of the others.

115 16. In a voting machine the combination 120 of two or more superposed tiers of voting devices, with a limiting mechanism for each, a transmitting or coupling member between the tiers extending from the end of the limiting mechanism of one tier to the end of the limiting mechanism of the adjoining tier and operatively connecting them and means to limit the movement of said transmitting 125 members.

17. A voting machine comprising two or 130 more rows of counters and counter actuators, limiting means parallel to and so movable with respect to each row and other means

- also movable therewith operatively coupling for movement the ends of the limiting means of adjoining tiers throughout the rows for multicandidate voting.
- 5 18. A voting machine comprising two or more tiers of counters and counter actuators, limiting means parallel with each tier and other means operatively coupling the ends of the limiting means of two or more tiers in 70 succession for multicandidate voting, and stationary means provided in connection with said limiting means to prevent the operation of more than a certain number of actuators in the tiers that are coupled.
- 10 19. In a voting machine, the combination of series of tiers of counter devices, with a limiting mechanism in connection with each tier, a transmitting member also in connection with each tier and its limiting mechanism and means connecting the members and limiting mechanisms of adjacent tiers, and means engaging certain of said members to prevent the operation of more than a given number of counting devices in all said tiers.
- 15 20. In a voting machine the combination with a series of tiers of counter devices with a limiting mechanism in connection with each tier, a transmitting member also for each tier and in connection with its limiting mechanism and connections between the members and limiting mechanisms of adjacent tiers and means for engaging certain of said members to prevent the operation of more than a given number of counting devices in all said tiers, adjustable means engaging the members to alter the interrelation of the said tiers and means for preventing the adjustment of the means during the voting period.
- 20 21. A voting machine comprising three or more tiers of voting devices having separators or actuators operable by a voter, a limiting mechanism for each tier comprising blocks for movement by the said separators, said blocks being arranged in series parallel with said tiers and being movable in either direction, and the blocks of each tier being connected at their ends to those of the other for normal coöperation therewith and means 95 for limiting the movement of the blocks in either direction.
- 25 22. A voting machine comprising two or more tiers of voting devices having separators or actuators operable by a voter, a limiting mechanism for each tier comprising blocks for movement by said separators, guides for the limiting mechanisms, said blocks being movable in either direction and the blocks of one tier being connected to 100 those of the other for normal coöperation therewith and devices for limiting the movements of said blocks in either direction.
- 30 23. In a voting machine, the combination of two or more tiers each embodying a series of counters, actuators and separators, and 105 each provided with a system of wedge blocks for certain operation by said separators, each tier having a transmitting member movable in either direction with said wedge blocks and coupling the same with the block at the 70 end of wedge blocks in the next tier and means engageable with said members to prevent movements of certain others in either direction.
- 35 24. The combination in a voting machine 75 of the tiers of counters and counter keys with separators movable with the keys, limiting blocks engaged and movable by said separators and adjustable stop means limiting the movement of the blocks and the communication 80 of movement from one tier of limiting blocks to the other.
- 40 25. The combination in a voting machine of the counters and the operating means, with the separators, the movable wedge blocks, 85 said separators being bodily movable longitudinally with said blocks and preserving the separators and blocks always in the same engagement and said blocks being beveled to admit the separators regardless of the degree 90 of the movement of said blocks.
- 45 26. The combination with the counter, of the counter actuator movable back and forth, the actuator key, the separator movable with the actuator and bodily movable independently thereof, wedge blocks engaged by said separator and with which it is bodily movable so as to permit the independent movement of said blocks without varying their relation to the separator.
- 50 27. A limiting mechanism for a voting machine comprising a longitudinally movable series of wedge blocks, and one or more transversely movable key operated separators to 100 enter between said blocks, said separators having a limit of one transverse movement while said blocks are adapted to several steps or movements and said separators and blocks being guided to retain their coöperating surfaces in the same relations of engagement regardless of the degree of motion of said blocks 110 whereby the degree of possible transverse movement in the separators is made constant.
- 55 28. The combination in a voting machine 115 of the counter, counter actuator and limiting blocks, with the separator operable in two directions, said actuator and separator forming permanent parts of the machine and said separator being movable bodily independently of the actuator for the purpose of completely operating said limiting blocks and counter successively.
- 60 29. A voting machine comprising two or more tiers of voting devices having actuators 120 operable by a voter, a limiting mechanism for each tier comprising blocks for movement by said separators, said blocks being movable in either direction and the blocks of one tier being connected to those of the other for nor- 125 130

mal coöperation therewith and means limiting the movement of said blocks in either direction.

30. In a voting machine the combination 5 of a series of counters and the actuators therefor adapted for movement by a voter, actuator operating means, a limiting mechanism and separators operable thereon and movable with said actuators the operating 10 surfaces of the said separators always maintaining the same position of engagement with said limiting mechanism regardless of the position of the parts of said mechanism.

31. In a voting machine the combination 15 of a series of counters and the actuators therefor adapted for movement by a voter, actuator operating means, a limiting mechanism and separators operable thereon and movable with said actuators said separators 20 being bodily movable laterally with respect to said actuators and always maintaining their operating surfaces in the same relation to their respective parts of the limiting mechanism regardless of the position thereof.

25. 32. In a voting machine the combination with a plurality of separate though adjacent rows of ballot keys and counters therefor, of spacing blocks, movable longitudinally of the rows, spreaders carried by the keys and movable laterally independently thereof and connections between adjacent rows of spacing 30 blocks.

33. In a voting machine the combination 35 with a plurality of separate though adjacent rows of ballot keys and counters therefor, of spacing blocks movable longitudinally of the rows, spreaders carried by the keys and movable laterally independently thereof, movable connections between the blocks of adjacent 40 rows of blocks, and means for rendering said connections stationary.

34. In a voting machine, the combination 45 of a plurality of superposed tiers or rows of voting mechanism with a system of limiting devices for each tier and operated by or with the voting mechanisms thereof and connecting devices capable of being set to connect the limiting devices for any two consecutive tiers, said connecting devices connecting the 50 limiting devices of each tier with the tier above it at one end, and with the tier below it at the other end, whereby any number of said tiers may be combined in a group.

35. In an interlocking system for voting 55 machines, a series of rows of independent locking devices and means for connecting each row to the row above at one end and to the row below at the opposite end, thus enabling any number of the rows to be combined in a group.

•36. The combination in a voting machine, of voting mechanisms arranged in single office groups and in party rows extending transversely to said office groups, the oper-

able parts of said voting mechanisms being 65 each provided with an interlocking wedge of substantially the same length, connections between the voting mechanisms in the same row to form an office group and interchangeable connections between the groups to limit 70 the number of mechanisms operable in each group or to permit the transmission of motion from the members of one group to those of an adjacent group.

37. The combination, of a series of voting 75 keys arranged in a series of parallel rows, an interchangeable interlocking system therefor, comprising interlocking blocks arranged in a corresponding series of parallel rows, a wedge attached to each key interlocking with said 80 blocks, said wedges being all of substantially the same length and means for communicating motion from the blocks in one group to those in an adjacent group.

38. The combination, in a voting machine, 85 of a series of voting mechanisms arranged in a series of parallel rows, each row representing an office group, interchangeable interlocking mechanisms individual to each row of keys, consecutive rows of interlocking 90 devices being interchangeably connected for group voting, each row of interlocking devices being connected to the row above at one end and the row below at the other end.

39. The combination, in an interlocking 95 mechanism, of a series of interlocking devices arranged in parallel rows, pivoted devices placed at both ends of each row connecting adjacent rows for interchangeable grouping, the device at one end connecting 100 to the row above and the device at the other end connecting to the row below.

40. The combination, in a voting machine, of a series of voting mechanisms arranged in a series of parallel rows, each row representing an office group, interchangeable interlocking mechanism interlocking the keys of a series of consecutive parallel rows, said interlocking mechanism being arranged in a plurality of rows, each row of interlocking 110 devices being adjacent to and coöperating with a corresponding row of voting mechanisms, means at end of the row connecting the row of interlocking mechanisms to the next row above and means at the other end to 115 connect with the next row below.

41. The combination, in a voting machine, of a series of voting mechanisms arranged in a series of parallel rows, each row representing an office group, interchangeable interlocking mechanism interlocking the keys of a series of consecutive parallel rows, said interlocking mechanism, being arranged in a plurality of rows, each row of interlocking 120 devices being adjacent to and coöperating with a corresponding row of voting mechanisms, means at end of the row connecting the row of interlocking mechanisms to the next row

above and means at the other end to connect with the next row below; said means being capable of being fixed against movement.

42. The combination, in an interlocking mechanism, of a series of interlocking devices arranged in parallel rows, devices placed at both ends of each row connecting adjacent rows for interchangeable grouping, the device at one end communicating motion to the row above and the device at the other end connecting to the row below.

43. The combination in a voting machine, of voting mechanisms arranged in single office groups and party rows extending transversely to said single office groups, an interlocking system therefor said groups being capable of combination or division by the releasing or fastening of movable abutments in said interlocking system, wedges on each of the voting mechanisms to interlock with the interlocking system, said wedges being of substantially the same length.

44. In a voting machine, the combination of the counters, the actuators therefor, pawls carried by the actuators and fixed stops with which said pawls coöperate, of separators movable with the actuator in one direction, and independently thereof in another, limiting blocks with which the separators coöperate and adjustable stop means for limiting the movement of the latter.

45. In a voting machine, a plurality of keys movable at right angles to the keyboard arranged in parallel office lines; wedges of equal length connected thereto, devices for interlocking with said wedges and means for holding said devices in rows parallel to the rows of keys interlocked, said parallel rows of interlocking devices being interchangeably related, permitting the combination of two or more office lines into one multicandidate group, or permitting the division of a multicandidate group into its respective office lines, said interlocking devices in each row having a progressive movement in obedience to successive keys voted in said row and means for communicating the interlocking effect in one row of interlocking devices to the adjacent rows of interlocking devices in the same multicandidate group to limit the total number of keys that can be voted in the group.

46. In a voting machine, a plurality of keys arranged in parallel office lines; wedges connected thereto, blocks for interlocking with said wedges and means for holding said blocks in rows parallel to the rows of keys interlocked, said parallel rows of interlocking blocks being interchangeably related, permitting the combination of two or more office lines into one multicandidate group, or permitting the division of a multicandidate group into its respective office lines, said interlocking blocks in each row having a progressive movement in obedience to suc-

cessive keys voted in said row and means for communicating the interlocking effect in one row of interlocking blocks to the adjacent rows of interlocking blocks in the same multicandidate group to limit the total number of keys that can be voted in the group.

47. In a voting machine, a plurality of keys arranged in parallel office lines, wedges connected thereto, devices for interlocking with said wedges and means for holding said devices in rows parallel to the rows of keys interlocked, said parallel rows of interlocking devices being interchangeably related, permitting the combination of two or more office lines into one multicandidate group, or permitting the division of a multicandidate group into its respective office lines, said interlocking devices in one row having a progressive movement in obedience to successive keys voted in said row and means for causing said progressive movement of the interlocking devices in one row to lock the keys of other rows in the same group against movement, and thus limit the total number of keys that can be voted in the group.

48. In a voting machine, a plurality of keys arranged in parallel office lines, and wedges connected thereto, devices for interlocking with said wedges arranged in parallel rows, said parallel rows of interlocking devices being interchangeably related, permitting the combination of two or more office lines into one multicandidate group, or permitting the division of a multicandidate group into its respective office lines, said interlocking devices in one row having a progressive movement in obedience to successive keys voted in said row and means for communicating the interlocking effect in one row of interlocking devices to the adjacent rows of interlocking devices in the same multicandidate group to limit the total number of keys that can be voted in the group.

49. In a voting machine, a plurality of keys arranged in parallel office lines, wedges connected thereto, devices for interlocking with said wedges and means for holding said devices in parallel rows to the rows of keys interlocked, said parallel rows of interlocking devices being interchangeably related, permitting the combination of two or more office lines into one multicandidate group, or permitting the division of a multicandidate group into its respective office lines, said interlocking devices in one row having a progressive movement in obedience to successive keys voted in said row and means for communicating the interlocking effect in one row of interlocking devices to the adjacent rows of interlocking devices in the same multicandidate group to limit the total number of keys that can be voted in the group.

50. In a voting machine, the combination of a plurality of movable indicators arranged

in adjacent rows, a plurality of rows of separable spacing blocks, connections between the blocks in said rows, and spacers movable by the indicators between the blocks and 5 movable by and with the blocks independently of the indicators.

51. In a voting machine, the combination of a plurality of movable indicators arranged in adjacent rows, a plurality of connected 10 rows of movable and separable spacing devices, spacers movable by the indicators between the blocks and movable by and with the blocks independently of the indicators and means for limiting the number of spacers 15 movable between the blocks.

52. In a voting machine, a key arresting mechanism consisting of a way or channel, a plurality of limiting devices therein, a spacer adapted for insertion in the way between 20 said devices and movable bodily by and with the latter and a vote indicating device for moving the spacer into the way and permitting its free movement therein.

53. In an interlocking mechanism, the 25 combination with a plurality of parallel ways and limiting blocks located therein, of spacers having portions extending between the blocks and movable by and with the latter in the ways, connections between the blocks in 30 adjacent ways and indicators movable transversely of the ways to operate the spacers, the adjacent indicators being arranged in rows parallel with the ways.

54. In an interlocking mechanism, the 35 combination with a row of limiting blocks, spacers having portions extending between the blocks, said spacers being guided for movement in a plane at right angles to the plane of the row and movable by and with 40 the blocks in the plane of the row, of an indicator for each spacer operable transversely of the row to insert the latter between the blocks and each having an operating portion, those of adjacent spacers being arranged in 45 a row parallel to that in which the limiting blocks are arranged.

55. In an interlocking mechanism, the combination with interlocking blocks and movable keys or indicators, of an interlocking 50 member for each key having portions engaging an indicator and displacing portions engaging the blocks, said member being guided to move bodily transversely of the direction of movement of its key without varying its relation to the blocks.

56. In an interlocking mechanism, the combination with a plurality of freely movable interlocking blocks and stops for limiting their movement, of a plurality of keys or 60 indicators, an interlocking displacing member for each key bodily movable by and with the blocks and guided to move and to maintain the same cooperative relation with the latter and with the key irrespective of the 65 amount of movement of the blocks.

57. In a voting machine, the combination with wedge shaped interlocking blocks and a voting key or indicator, of an interlocking member having a portion in sliding engagement with the key or indicator and a displacing portion adapted to engage with the wedge shaped blocks, said member arranged to maintain constant engagement with both and permitting the movement of either the key or block or the simultaneous movement 70 of both key and block transversely to the other.

58. The combination with the voting device, of interlocking blocks and an interlocking displacing device operable by the voting 80 device to separate them, capable of a movement laterally of the separating movement and always presenting its interlocking surface at the same angle to engaging surfaces of the blocks.

59. The combination with two or more counters, of an actuator and a separator for each, the separator in each case having a fixed relation to the actuator in one direction of movement, the limiting wedge blocks engaged by said separators and means holding 90 said separators in engagement with the blocks whenever the same are movable and maintaining the same interlocking relations thereof at all times.

60. A limiting mechanism for voting machines comprising a longitudinally movable series of wedge blocks and one or more transversely movable key operated separators to enter between the said blocks, said separators having a limit of one movement transversely of the blocks while both said blocks and separators are adapted to move bodily several longitudinal steps or movements, connection between said separators and blocks permitting the parts to maintain the same relations of engagement regardless of the degree of motion of the blocks.

61. The combination in the voting machine of a voting key or indicator having a stem and a guide extending transversely thereof and an interlocking member operated by said key and having sliding engagement with the guide.

62. In an interlocking device for voting machines, the combination with movable blocks, an interlocking member, having a portion adapted to engage with a movable guide, and a displacing device adapted to engage with the movable blocks, and a guide 115 extending parallel with the blocks and movable transversely of their plane of movement with which the said first mentioned portion 120 engages.

63. In a voting machine, the combination with the blocks, and a key having a guide, of an interlocking member having a projection by which it engages movably with the guide on the key, and a displacing projection by which it engages with the blocks so that said 125 130

interlocking member may maintain constant engagement with both its key and the interlocking blocks.

64. In an interlocking system, the combination with a key, an interlocking member having a positive engagement with its key, when said key is moved forward or back, and a sliding engagement with said key in the direction transverse to the movement thereof and limiting means with which said member engages.

65. In an interlocking system, the combination with a key or indicator, of an interlocking member movable with and bodily relatively of the key and having the portion engaging with its key, and means by which it engages with coöperating interlocking devices, the connection and arrangement permitting the movements of the member relatively to the key and the other interlocking parts without variation of their coöperative relation.

66. In a voting machine, interlocking mechanism for multicandidate group voting, comprising a plurality of parallel single candidate groups of interlocking slides or wedge blocks, connections between said single candidate groups to transmit the movement from one group to the next adjacent group, the movement in the intermediate groups being freely transmissible at either end thereof, and securing devices for the end slides or wedge blocks of the whole series whereby the spreading of the slides or wedge blocks will be limited to a predetermined amount.

67. In an interchangeable interlocking system, the combination of a plurality of movable keys or indicators arranged in parallel rows, and a wedge spacer operable by each key and extending equally distant therefrom,

interlocking blocks also arranged in a plurality of parallel rows with which the wedge spacers coöperate and connections between the rows of blocks to cause the wedge spacers to be moved in one or more rows as successive indicators are operated in one row.

68. In a voting machine, the combination with a plurality of separate though adjacent rows of ballot indicators, of limiting devices movable longitudinally of the rows, spacers operable by the indicators between the limiting devices and permitted movement laterally independently thereof and connections between adjacent rows of limiting devices for communicating motion from one to the other.

69. In a voting machine, a plurality of rows of interlock devices movable in a given plane, indicator keys, separators movable with the keys to separate the interlock devices and movable also in the plane of movement of the interlock devices and means for operatively connecting the rows of interlock devices.

70. In a voting machine, a key arresting mechanism embodying a plurality of limiting devices, a spacer adapted for insertion between said devices and movable bodily by and progressively with the latter in either direction and an indicating device for moving the spacer into coöperative relation with said devices and permitting its free movement therewith.

In testimony that I claim the foregoing as my own I have hereto affixed my signature in the presence of two witnesses.

WILLIAM H. STRONG.
